United States Patent Office.

O. G. NEWTON, OF EDINBURG, MISSOURI.

Letters Patent No. 83,530, dated October 27, 1868.

IMPROVEMENT IN TUYERES.

The Schedule referred to in these Letters Patent and making part of the same.

To all whom it may concern:

Be it known that I, O. G. NEWTON, of Edinburg, in the county of Grundy, and State of Missouri, have invented a new and useful Improvement in Tuyeres: and I do hereby declare that the following is a full, clear, and exact description thereof, which will enable those skilled in the art to make and use the same, reference being had to the accompanying drawings, forming part of this specification.

The object of this invention is to provide an improvement in tuyeres, whereby the cinder may be more readily removed, and the blast regulated, than can be done with those now in use.

It consists of a ball-valve, provided with cavities to receive the cinder, arranged on a rotary shaft, having a vertically-adjustable bearing, whereby it can be readily raised and lowered to be rotated for the discharge of the cinder, and also for regulating the passage of air to the fire.

Figure 1 represents a sectional elevation of my improved tuyere, and

Figure 2 represents a plan view of the same, with the cap removed.

Similar letters of reference indicate corresponding parts.

A represents the air-vessel, of which B is the cover, provided with the usual opening, C, for the air to pass to the fire.

D represents a weighted valve at the bottom of the air-vessel, for regulating the blast, and for the discharge of ashes and cinders.

E represents the ball-valve, provided with the cavities F for the reception of the cinders, and which is supported axially on the horizontal shaft G, having a bearing in an adjustable slide, H, and also in the opposite side of the air-vessel A.

The shaft G is prolonged a sufficient distance to be provided on its end, outside of the walls of the forge, with a crank, I, for turning it.

The slide H may be fitted to operate in the groove provided for it, with sufficient friction to maintain the shaft G in any position desired, or it may be provided with other means for holding it.

By this means the air-blast may be readily regulated and adjusted as required, and the fire may be with equal facility cleaned of cinders and other foul matter, by lowering and turning the valve to discharge the cinders below, the blast maintaining the fire in its position, and from falling down with the valve.

I am aware that the devices, marked in the drawing A, B, E, F, and G, are not new, but are found in the patent of J. Lubach, November 10, 1841, and I do not claim them separately; but

What I do claim is—

The combination of those parts with the adjustable bearing for the shaft G, as arranged and described.

The above specification of my invention signed by me, this 3d day of July, 1868.

O. G. NEWTON.
